MINE COUPLER

Carl N. Rydin, Warrenville, Ill.

Application July 29, 1949, Serial No. 107,457

1 Claim. (Cl. 213—104)

1

This invention appertains to car couplers and more particularly to couplers of a type especially adapted for mine cars, railroad motor cars and the like.

One of the primary objects of my invention is to provide a coupler having a novel jaw and knuckle construction, whereby meeting couplers of cars are quickly and automatically locked.

Another object of my invention is to provide a coupler so constructed that disengagement of the jaws of mating couplers is prevented incident to the travel of cars over high or low portions of a railroad track.

Another salient object of the invention is to provide a car coupler having a jaw receiving chamber therein functioning to limit the up and down movement of a mating coupler jaw, the walls of the chamber forming faces to facilitate the guiding of the jaws of meeting couplers to their interlocking position.

A further object of the invention is to provide spring means for normally urging and holding the jaws or knuckles in their locked position and to provide means whereby the springs and jaws can be quickly replaced if damaged or broken.

A further object of the invention is to provide means for holding the coupler jaws in place and in coupled position should the pivots for said jaws break or become accidentally displaced through any reason.

With these and other objects in view, the invention consists in the novel construction, arrangement and formation of parts, as will be hereinafter more specifically described and claimed and illustrated in the accompanying drawings, in which drawings,

Figure 1 is a fragmentary plan view of a pair of cars equipped with the novel couplers and draft rigging, parts of the view being shown in longitudinal section and said section being taken on the line 1—1 of Figure 2, looking in the direction of the arrows.

Figure 2 is a vertical sectional view taken on the line 2—2 of Figure 1, looking in the direction of the arrows.

Figure 3 is a fragmentary horizontal sectional view through mating couplers, the section being taken on the line 3—3 of Figure 2, looking in the direction of the arrows, the view being on a larger scale than Figures 1 and 2.

Figure 4 is a transverse sectional view taken on the line 4—4 of Figure 3, looking in the direction of the arrows.

Figure 5 is a fragmentary detail vertical sectional view taken on the line 5—5 of Figure 3, 55 to permit the ready insertion of this pin in the

2

looking in the direction of the arrows illustrating the construction of the pivot pin and the means for holding a coupler jaw or knuckle in position, should the pivot pin become displaced.

5 Figure 6 is a fragmentary vertical longitudinal sectional view through adjacent couplers taken on the line 6—6 of Figure 3, looking in the direction of the arrows.

Figure 7 is a top plan view of one coupler 10 showing its jaw or knuckle in a retracted, uncoupled position, parts of the figure being shown broken away.

Figure 8 is an end elevational view of one of the couplers, with the knuckle retracted.

15 Figure 9 is a detail plan view of one of the coupler jaws or knuckles, said view being on a greater scale than Figures 1 and 2, but on a smaller scale than Figures 3 to 8, inclusive.

Figure 10 is an inner side elevational view of 20 the coupler jaw shown in Figure 9.

Figure 11 is an outer side elevational view of the coupler jaw shown in Figures 9 and 10.

Referring to the drawings in detail, wherein 25 similar reference characters designate corresponding parts throughout the several views, the numerals 15 and 16 indicate a pair of companion couplers, which are carried by the adjacent ends of cars 17 and 18, by draft rigging 19 and 20.

The couplers are each of identically the same 30 construction and hence only one of said couplers will be described in detail.

Each coupler includes a shank 21, and an integral hollow coupling head 22. Rockably mounted within the hollow head 22 is a coupling knuckle 23. Formed on the inner end of 35 the knuckle 23 is a vertically extending hinge barrel 24. To facilitate assembling and to reduce cost of manufacture, the bore 25 through the hinge barrel is of an oval shape in cross section. The head itself, substantially at its longitudinal axis is provided with upper and lower bearing openings 26 and 27, of a substantially circular shape in plan. A sturdy pivot 28 is provided for rockably connecting the knuckle with the head and the bore 25 is adapted to register

40 with the openings 26 and 27 for the reception of the pivot pin 28. The pivot pin for the major portion of its length is of an oval shape in cross section to correspond to the cross sectional configuration of the bore 25, and the pivot pin adjacent to its opposite ends is of a circular shape 45 in cross section for turning movement in the bearing openings 26 and 27. The pivot pin also preferably tapers toward its lower end so as

50 to permit the ready insertion of this pin in the

openings 26 and 27 and the bore 25. The knuckle and pivot pin turn as a unit and the pivot pin has formed on its upper end a laterally extending hand lever or crank 29 which rides on top of the coupler head. This lever or crank 29 can be provided with reinforcing ribs which also function as finger pieces. The pivot pin 28 is detachably held in position against accidental movement, in any desired way, such as by the use of a cotter pin 30 (see Figure 5). Obviously, by moving the lever or crank 29, the knuckle can be swung back and forth.

On one side of the longitudinal axis of the head 22 and on the same side as the knuckle, is a forwardly extending guide nose 31 and the nose terminates in a substantially vertical leading edge 32, from which flares outwardly in opposite directions, the inclined guide faces 33 and 34. Directly in rear of the guide face 33 is a reinforcing and stop rib 35. The knuckle 23 swings back and forth in the nose 31 and when the knuckle is in its outwardly extending position, the same projects beyond the nose toward the longitudinal axis of the coupler head. By referring to Figures 7 and 8, and detail views 9 to 11, it can be seen that the forward end of the knuckle 23 has formed thereon a substantially hook shaped jaw 36 and this jaw has a front leading inclined face 37, the purpose of which will later appear.

On the opposite side of the longitudinal axis of the coupler head 22 from the guide nose 31, is an inwardly directed substantially V-shaped recess 38, which is adapted to receive the nose 31 and knuckle of a mating coupler. As the recess 38 is of a substantially V-shape in cross section, the same provides outwardly flaring side guide walls 39, which correspond to the shape of the guide nose 31. It is to be also noted at this point, that the inner guide face 34 of the nose 31 is provided with an opening 40, which communicates with the interior of the hollow head for permitting movement of the jaw or knuckle into and out of the head.

Great stress is laid on the V-shape recess 38 and the coupler head has formed thereon upper and lower outwardly projecting walls 41, connected by top and bottom walls 42 and 43. These walls 41, 42 and 43 in conjunction with the V-shaped recess 38 form an elongated vertically extending compartment or pocket and a guideway for the guide nose 31 and knuckle of a mating coupler. As stated, this is important, as will be now set forth. In mines, it often happens that the track is uneven particularly at the juncture of rails, and high and low spots will be found. As the couplers of adjacent cars move up and down the compartments prevent displacement of the knuckles and couplers one from the other and hence the uncoupling of the cars is prevented.

The knuckle 23 of each coupler is normally urged outwardly to a coupling position with its jaw 36 protruding beyond the nose 31 by a relatively heavy expansion spring 44. This spring is coiled about a guide rod 45 which extends through an opening 46 in the knuckle 23, directly in advance of the hinge barrel 24. The inner end of the guide rod 45 is provided with a flat-head 47 and one end of the spring 44 bears against the head and the opposite end of the spring bears against the knuckle. The outer end of the guide rod 45 is provided with a tapered head 48. One wall of the opening 40 has formed therein a slot 49 of a width correspond-

ing to the diameter of the rod 45 and this slot terminates in a seat 50. By sliding the rod 45 in the slot 49, the tapered head 48 can be fitted in the seat 50, against the tension of the spring 44. After assemblage of these parts the spring bearing against the knuckle will swing the knuckle to a coupling position.

While the knuckle can be made in various manners, it is desirable that the same be made light as possible, and to reinforce the same, spaced ribs 51 can be provided on one side thereof.

In view of the rough usage that couplers are subjected to and uneven track conditions, it may be possible to lose or break a pivot pin 28. In such a contingency, means is provided for preventing the pulling out of the knuckle. This means includes V-shaped recesses 52 in the knuckle, adjacent to its upper and lower edges and in close vicinity to the hinge barrel 24. The hollow coupler head itself is provided with substantially V-shaped lugs 53. When a knuckle is in its coupling position, the recesses 52 receive the lugs 53 and these lugs engaging the walls of the recesses, effectively prevent a knuckle from being pulled out and the lugs and recesses act as latches.

Upon the coming together of coupler heads, the guide noses 31 will move into the recesses 38 and the inclined outer sides 37 of the knuckle jaws 36, will strike and ride on one another, momentarily forcing the knuckles back against tension of the springs 44. As soon as the jaws 36 pass one another, the springs 44 will force the knuckles out and into interlocking engagement with one another and hence the couplers will be operatively connected. To disengage the couplers, the hand levers or cranks 29 can be pulled back to move the knuckles inwardly against tension of their springs.

While the couplers may be mounted in various manners on cars, it is preferred to use the draft rigging 19 and 20, which is especially adapted for use on mine cars and on motor rail cars used for work purposes. As illustrated, the inner end of each shank 21 of the couplers is provided with a vertical enlargement 54, constituting a pull-head and this enlargement has formed therein a vertically extending bore. The enlargement is bifurcated horizontally to provide a receiving slot 55 for the drawhead 56 of a drawbar 57. The drawbar 57 constitutes a part of the draft rigging 19 and as the draft rigs 19 and 20 are identical in construction, only one will be described in detail. A pivot pin 58 extends through the enlargement 54 and the drawhead 56 and consequently the coupler is mounted for swinging movement on the drawbar 57. The drawbar 57 extends longitudinally of a car and is mounted in a novel manner on the car. This mounting embodies a rugged supporting bracket 59. While the bracket can take different shapes, the same preferably includes spaced parallel side walls 60, a connecting top wall 61 and a rear wall 62. The rear wall 62 and the side walls 60 can be provided with attaching feet 63 to permit the secure bolting of the bracket to an adjacent frame part of a car. As illustrated, bolts 64 connect the bracket to a transverse channel-beam 65 of the car. The outer end of the top wall 61 of the bracket is provided with curved back-ears 66, which are adapted to embrace a transverse brace bar 67, which can be welded or otherwise rigidly fastened to the longitudinal channel beam 68 of a car. Bolts 69 connect the

ears 66 with the top wall 61 of the bracket directly in rear of the transverse brace bar 67. Also forming a part of the bracket 59 is a front flange or wall 70, and the same is rigidly connected with the top wall 61 and the side walls 60. This front wall 70 and the inner or rear wall 62 are provided respectively with aligned guide openings 71 and 72. The drawbar 57 slidably extends through these openings and through inner and outer guide thimbles 73 and 74, which are also mounted for movement in the openings 71 and 72. The outer thimble 73 bears against a part of the drawhead 56 and the inner end of the thimble is provided with an annular flange 75, which normally engages the inner face of the front wall 70. The inner thimble 74 also has formed therein an annular flange 76, which normally engages the inner face of the rear wall 62. A washer 77 and a nut 78 are placed on the inner end of the drawbar 57 for engagement with the thimble 74. An expansion spring 79 is coiled about the drawbar 57 and is confined between the thimbles 73 and 74.

It can be seen that upon the coming together of couplers that shock will be absorbed due to the inward movement of the thimble 73 against the tension of the spring 79. Shock will be absorbed on the outward pulling movement of the couplers due to the movement of the thimble 74 against the tension of the spring 79.

From the foregoing description, it can be seen that I have provided a novel coupler head especially suitable for mine and like cars.

Changes in details may be made without de-

5
10
15

parting from the spirit or the scope of this invention, but what I claim as new is:

In a coupler, a hollow coupler head having a forwardly projecting tapered guide nose on one side of its longitudinal axis and a nose receiving recess on the opposite side of its longitudinal axis, the inner face of said nose having an opening communicating with the interior of the hollow head, a knuckle received in said head having a hinge barrel on its inner end and a jaw on its outer end, pivot means connecting the barrel with the head, said knuckle intermediate the barrel and jaw being provided with a guide opening, a guide rod slidable in said opening, a stop on the inner end of said rod, tension means on said rod interposed between the stop and knuckle, and the outer end of said rod having a head, one wall of said opening in the nose being provided with a slot for receiving the rod and a seat for the head.

CARL N. RYDIN.
